UNITED STATES PATENT OFFICE.

RUPERT SCHULTHEISS, OF TACOMA, WASHINGTON.

STARTING-VALVE FOR COMPOUND LOCOMOTIVES.

SPECIFICATION forming part of Letters Patent No. 769,360, dated September 6, 1904.

Application filed December 21, 1901. Serial No. 86,840. (No model.)

To all whom it may concern:

Be it known that I, RUPERT SCHULTHEISS, a citizen of the United States of America, and a resident of Tacoma, in the county of Pierce 5 and State of Washington, have invented certain new and useful Improvements in Starting-Valves for Compound Locomotives, of which the following is a specification.

My invention relates to improvements in starting-valves for compound locomotives adaptable to regulate induction and eduction of motive fluid, and has especial reference to a valve of this class adapted for embodiment with compound engines.

15 Among numerous objects attained by this invention is the production of a balanced rotary valve of simple and inexpensive construction adaptable to either a single or compound engine and readily adjustable at will 20 to run a compound engine either simple, single, or normal.

The above-mentioned and other objects equally as desirable are attained by the constructions, combinations, and arrangement of 25 parts, as disclosed on the accompanying drawings, set forth in the following specification, and succinctly pointed out in the appended claims.

With reference to the drawings filed here- 30 with and bearing like reference characters for corresponding parts throughout, Figure 1 is a view of a portion of the head end of a compound locomotive in front elevation and shown with my improved valve embodied 35 with the motive cylinders thereof and one side of said end in vertical section, taken transversely the bores of respective cylinders and longitudinally the attendant valve as set to operate the engine normal or compound. 40 Fig. 2 indicates the cylinders of a compound engine in longitudinal section with a modified form of valve embodied therewith and set to operate said engine normal. Fig. 3 is a side view of the valve as preferably formed 45 and indicates the seat thereof in longitudinal section on line 3 of Fig. 4 and the valve set to operate a compound engine normal. Fig. 4 is a transverse section of the valve and its seat on line 4 of Fig. 3 viewed as the arrows 50 fly and indicates the plug of the valve sub-

stantially midway its path of travel. Fig. 5 is a similar section to Fig. 4, taken on line 5 of Fig. 3 looking as the arrows indicate and shows the intercepting-shell set to operate a compound engine normal and the valve-plug 55 midway its path of travel. Fig. 6 is a like section on line 6 of Fig. 3 viewed as the arrows fly, and Fig. 7 indicates a like view of the valve in transverse section on line 7 of Fig. 3 looking as the arrows point. 60

This valve comprehends a rotative cylindrical valve-plug, as 10, arranged to receive motive fluid interiorly and having suitable ports for admission and distribution and a movable intercepting-shell, as 12, embodied 65 therewith in a seat, as 13, and having apertures in the wall adapted to coact with said ports and with suitable fluid-passages correlatively to adjustments of the shell, and thereby regulate induction and eduction of motive 70 fluid. As now considered valve-plug 10 is rendered round and revoluble and operates reciprocally through an arc of predetermined length, and shell 12 is formed cylindrical, so as to receive a portion of said plug freely 75 but snugly and likewise fit in seat 13, and thereby conveniently arranged to lie free for independent movement in said seat, which is conveniently formed in communication with suitable fluid-passages leading to and from 80 the engine-cylinders, as high and low pressure cylinders, (marked *a* and *b*, respectively, in Fig. 1 or *c* and *d*, respectively, in Fig. 2.)

In the present embodiment valve-plug 10 is formed with both ends closed and with suitable 85 partitions, as 9 and 9', Fig. 1, or 9", Fig. 2, arranged to afford separated chambers in the valve, as an induction-chamber 14, adapted to receive live fluid primarily for distribution to the cylinder of a single engine or the high-pressure cylinder of a compound engine; an intermediate chamber 15, Fig. 1, or 15', Fig. 2, to receive the exhaust from a high-pressure cylinder or live fluid primarily and also intermixingly with said exhaust, if desired, for distribution therewith to the low-pressure cylinder when the engine is operating compound or for distribution of said live fluid alone to the low-pressure cylinder when the engine is operating simple, and an exhaust-chamber 16, 90 95 100

Fig. 1, or 16', Fig. 2, adapted to receive fluid exhausting from both or either cylinder and to act secondary to either the induction-chamber 14 or intermediate chamber 15, or both, 5 as determined by the nature of the engine, whether single or compound, or by setting the intercepting-shell to operate compound engines normal or simple.

From the foregoing it will be understood 10 that the passages for motive fluid leading to and from the cylinder or cylinders of an engine incorporating my valve are arranged in conjunction with a seat, as 13, and in conformity with the ports and apertures as arranged, respectively, in the plug and shell of the valve in accordance with the nature of the engine. In the present instance induction-chamber 14 is arranged in one end of plug 10, and a transversely-disposed port 19 is suitably placed in 15 the wall of said chamber, Fig. 4, so as to lie constantly in communication with a live-fluid passage, as 20, leading from a source of supply to seat 13, and oppositely-disposed ports 22 are formed in said wall, so as to alternately 20 and intermittently register with respective fluid-induction passages 20', which lead from said seat to opposite ends of an engine-cylinder, as a high-pressure cylinder *a* or *c*, Figs. 1 and 2. Exhaust-passages 23 are arranged 25 to lead the fluid exhausting from respective ends of said cylinder back to valve-seat 13, and the plug and shell of the valve are suitably formed to direct this fluid to intermediate chamber 15, Fig. 1, or 15', Fig. 2, for 30 distribution for further use in the engine, or to chamber 16, Fig. 1, or 16', Fig. 2, for exhaust, and thereby render it possible to operate the engine single.

In the preferred construction of the valve-plug partition 9 is disposed transversely thereof of adjacent one end to form induction-chamber 14 at that extremity of the valve, and partition 9' is disposed longitudinally the plug between said transverse partition and the opposite end, so as to form intermediate and exhaust chambers, as 15 and 16, respectively, Figs. 1, 3, 5, and 7, and intercepting-shell 12 is rendered of suitable length to cover said plug over said chambers 15 and 16. In the 45 wall of chamber 16 a suitable exhaust-port 35 is arranged, Fig. 7, and apertures, as 36, are formed in the opposing wall of shell 12 relatively thereto and in conformity with an exhaust-passage 27, leading from seat 13, so as 50 to conveniently leave said chamber open to final exhaust. Apertures, as 26, Fig. 7, are formed in the wall of shell 12 at suitable opposite points and are elongated circumferentially the shell by channels 25, formed in the 55 periphery and adapted to bring said apertures into communication with exhaust-passages 23, leading from the high-pressure cylinder, when the shell is adjusted to run the engine single or simple, and ports 28 are arranged in the 60 wall of plug 10 at suitable points to alter-

nately register with respective apertures 26 when the shell is so adjusted. These ports 28 are formed so as to lead to exhaust-chamber 16, and thereby direct the fluid exhausting from the high-pressure cylinder for final discharge when the shell is adjusted to operate the engine simple or single. 70

To conveniently adapt the valve for operating the engine compound, an aperture 26' is formed in shell 12 between the apertures 26 75 and is arranged so as to register with one passage 23 when the shell is properly adjusted to cause one of the apertures 26 to lie directly in line with the opposite passage 23, as indicated in Fig. 7, and ports 24 are formed in 80 the wall of plug 10 at suitable points, so as to intermittently register with a respective aperture 26 or 26' and admit the fluid exhausting through passages 23 to chamber 15 for distribution and further use in the engine. 85

In the present instance live steam is admitted direct from the source of supply to intermediate chamber 15 through an aperture, as 30 or 31, Fig. 5, formed in shell 12 at suitable points to register with a supplemental 90 live-fluid passage, as 29, when the shell lies in either of its adjusted positions. These apertures are controlled by plug 10, in the wall of which oppositely-disposed ports 28' are arranged to intermittently admit fluid to chamber 15 from respective passages 29 and 31 when either of said apertures register therewith, and thereby render it possible to distribute said fluid to the low-pressure cylinder *b* when the engine is running either simple or compound. The fluid admitted to intermediate chamber 15 is conducted to the low-pressure cylinder by passages, as 34, Fig. 6, arranged in communication with respective ends of said cylinder and with valve-seat 13, Fig. 100 6. Apertures, as 33, are formed in pairs at suitable points transversely the wall of shell 12, so as to register with these passages 34 when said shell lies in either of its adjusted 105 positions, and ports 32 are formed at opposite 110 points through the wall of plug 10 to intermittently release fluid through respective apertures 33, and thereby supply the low-pressure cylinder. From the foregoing it will be understood that when shell 12 is adjusted to 115 run the engine simple the exhaust from the high-pressure cylinder passes into chamber 16 for final exhaust and only live fluid is admitted to intermediate chamber 15, which is then distributed to the low-pressure cylinder. Should, however, shell 12 be adjusted to run 120 the engine normal, the exhaust from the high-pressure cylinder passes into the intermediate chamber 15, and live fluid is also admitted thereto from supplemental passages 29 and 125 30 intermixes with said exhaust and passes therewith to the low-pressure cylinder, as heretofore set forth. The low-pressure cylinder exhausts through passages 39, Fig. 5, into chamber 16, which is constantly open to passage 130

27, as heretofore set forth. Shell 12 is formed with apertures 38, arranged in pairs in the wall at suitable points to give said passages 39 a delivery-way through said shell at all times, and ports, as 37, are conveniently provided in the wall of plug 10 at suitable opposite points to intermittently register with respective apertures 38 to give a free exhaust at proper times.

10 As now considered valve-plug 10 is operated by means of a crank, as 40, fixed to a suitable stem of the plug and operably connected to any suitable reversing-gear, and the intercepting-shell 12 is adjusted through the medium of a similar crank 41, attached to the stem thereof and operably connected to any suitable mechanism for turning the shell as desired to vary the application of motive fluid.

It will be understood that the several passages, apertures, and ports are arranged in relative positions in conformity with the length of adjustment of the shell and travel of the plug and that the valve is practically balanced at all times owing to the passage of the motive fluid therethrough; furthermore, that the valve can be formed without the reference to the supplemental passage 29, and thereby made to operate an engine single, or it can be arranged to distribute fluid from said passage 30 only when shell 12 is adjusted to operate a compound engine simple and to close said passage when said engine is operating normal. This modification will be readily understood by those skilled in the art to which this invention pertains, as it simply requires in the first instance, the omission of ports 28' and in the latter instance the omission of aperture 31.

When the engine is operating single, the exhaust from cylinder *a*, Fig. 1, passes through passages 23, Fig. 7, to apertures 26, respectively, and is admitted to exhaust-chamber 16 through ports 28. When it is desired to run the engine normal, shell 12 is set to register aperture 26' with one passage 23, Fig. 7, and thus cause the fluid exhausting from said cylinder to pass into intermediate chamber 15 through ports 24, and is distributed to the low-pressure cylinder through ports 32, Fig. 6, apertures 33, and passages 34, and said cylinder exhausts to chamber 16 through passages 39, Fig. 5, apertures 38, and ports 37. If the valve is arranged to admit fluid from passage 29 when shell 12 is adjusted to run a compound engine normal, the said fluid will enter intermediate chamber 15 through aperture 31 and ports 28', Fig. 5, and thence pass to the low-pressure cylinder, as heretofore set forth. If the valve is arranged to admit said fluid to the intermediate chamber only when the shell is adjusted to operate a compound engine simple, the aperture 31 is omitted, and the fluid will only be admitted through said ports 28' when aperture 30 is brought into communication with passage 29.

65 Having thus described my invention, what

I claim as new, and desire to secure by Letters Patent of the United States, is—

1. In combination with a cylinder having inlet and outlet passages leading therefrom, and a source of supply, a plug formed with a hollow chamber provided with a pair of ports adapted to alternately register with the said inlet-ports, and a port in communication with a source of supply at all times, a second chamber in said plug, a shell inclosing said last-named chamber and having an opening communicating with said outlet, said last-named chamber being formed with an opening adapted to register with the opening of said shell, and means whereby the exhaust is educted from said last-named chamber.

2. In a valve of the type set forth, an oscillatory plug formed with independent chambers disposed one in advance of the other longitudinally of the plug, a shell inclosing one of said chambers, said chambers and shell being formed with openings adapted to register at different adjustments of said shell, means for adjusting said shell to its different positions, and means for oscillating said plug, in combination with a seat for said plug and shell.

3. In combination with the high and low pressure cylinders, and a source of supply, a valve, a shell inclosing the same, means for conveying the fluid through the valve to the high-pressure cylinder then from the cylinder again through the valve and into the low-pressure cylinder, a chamber in said valve, means for conveying the fluid from said low-pressure cylinder to said chamber, means for actuating the valve and shell respectively, and means whereby the fluid is conveyed from said high-pressure cylinder to said valve-chamber.

4. In combination with the high and low pressure cylinders, and a source of supply, a valve comprising a plug formed with upper, intermediate and exhaust chambers, a shell inclosing the last-named chambers, said upper chamber being in communication with the high-pressure cylinder and the source of supply, exhaust-ports leading from said high-pressure cylinder, said shell and last-named chambers having openings adapted to register with each other and with said exhaust-ports at different adjustments of the shell, means whereby communication is established between said intermediate chamber and the low-pressure cylinder, and between said last-named cylinder and the exhaust-chamber, means for actuating said plug, and means for adjusting said shell to its different positions.

5. In combination with a cylinder and the exhaust-ports leading therefrom, a valve formed with a pair of chambers, a shell inclosing the same, and being formed with a pair of inlet-ports registering with said exhaust-ports, one chamber of said valve having a pair of ports alternately registering with the ports of said

- shell, exhaust-ports arranged in pairs in said shell, ports in said valve-chamber adapted to alternately register with said last-named exhaust-ports, means for adjusting said shell,
5 means for permitting the fluid to pass from said first-named exhaust-ports directly into the other chamber when the shell is adjusted, and means for actuating said valve.
6. In combination with the high and low pressure cylinders and a source of supply, a plug formed with a plurality of chambers, one of said chambers communicating with said high-pressure cylinder and source of supply respectively, an adjustable shell surrounding the remaining chambers, said shell and

last-named chambers having openings, said shell in one position having its openings communicating with the openings of one of said last-named chambers, and in another with the openings of the other of said last-named chambers, means whereby communication is established between the low-pressure cylinder and said last-named chambers, and means for actuating said plug and shell respectively.

Signed at Tacoma, Washington, this 28th ²⁵ day of October, 1901.

RUPERT SCHULTHEISS.
